UNITED STATES PATENT OFFICE.

SCOTT V. SMITH, OF BRIDGEPORT, ILLINOIS.

AUTOMATIC VACUUM-CONTROLLED VALVE.

Application filed June 28, 1927. Serial No. 202,111.

The present invention is directed to improvements in automatic vacuum controlled valves.

The primary object of the invention is to provide a valve of this character which is placed in a line between a liquid containing reservoir or tank and the vacuum pump, the construction being such that should the tank or reservoir become empty the valve will automatically close to prevent air from the tank or reservoir from being drawn into the vacuum pump.

Another object of the invention is to provide a valve of this character so constructed that it will operate as soon as the reservoir has been replenished, the air in the line being displaced by the liquid in order to prevent air being drawn into the pump upon opening of the valve.

20 In the accompanying drawing:

Figure 1 is a longitudinal sectional view through the valve.

Figure 2 is a similar view of a slightly modified form of the valve.

25 Referring to the drawing, 1 designates a casing having an inlet 2 and outlet 3, there being a valve seat 4 in said casing. This seat is provided with an annular groove 5 in which snaps the wire ring 6 carried by the upper end of the cylindrical screen 7, the lower end of which fits around an upstanding flange 8 carried upon the bottom of the casing in order to stabilize the screen or strainer.

The upper end of the casing is formed with 35 an integral guide sleeve 9 having a rim 10, threaded as at 11. Threaded upon the rim 10 is a cap 12 including a dome 13. Slidable in the sleeve 9 is a hollow cylindrical valve 14, the outer surface of the side walls thereof 40 having an annular groove 15 therein and with which the outer ends of the upper ducts 16 communicate. These ducts are inclined inwardly and downwardly, there being lower ducts 17 formed in the wall of the valve which 45 are located adjacent the bottom closure 18 thereof. The upper edge of the valve wall terminates in an inturned flange 19 which forms a rest for the flexible packing sheet 20, said sheet having its marginal portion 50 clamped between the rim 10 and cap 12. A weight 21 is secured to the packing sheet 20 by a bolt 22 and washer 23.

A sheet metal cone 24 is provided and has 55 its periphery also clamped between the cap 12 and rim 10, the apex thereof having an air displacement orifice 25. The cap is provided

with a plurality of grooves 25' which lead from the interior of the dome to the annular groove 26 formed in said cap, there being inclined vents 27 formed in the cap which 60 communicate with said dome. These vents serve to prevent any moisture collecting upon the upper surface to drain, and since the vents are inclined moisture will be prevented from entering therethrough. The dome 13 65 is preferably hexagonal in contour in order that a wrench may be applied thereto to remove or replace the same. It will be obvious that when a valve is in a line between a vacuum pump and liquid containing reservoir 70, not shown, and the pump is operating to create suction in the outlet 3 of the casing 1, the valve will remain seated and will in no way be affected by the vacuum. However, as soon as liquid from the reservoir enters the 75 casing through the inlet 2 and passes through the screen 7 the valve 14 will be lifted from the seat 4, permitting the vacuum to draw the liquid through the seat and to its point of use. Should the liquid containing reservoir 80 or tank become empty and air be admitted to the casing instead of liquid the gravity pressure of the liquid will consequently be lacking and the valve 14 under its own weight will drop upon the seat 4, thus cutting off the 85 air until the line has been again filled with liquid and air displaced from the line. The inflowing liquid will then raise the valve in order that the liquid can again be drawn by suction through the line.

90 Any moisture which may collect in the annular chamber 28 formed between the rim 10 and cap 12 will pass through the ducts 16 into the body of the valve 14 and from thence will discharge through the ducts 17 when the valve is seated. Under certain conditions it may be necessary to balance the valve and in Figure 2 of the drawing I have illustrated means for so doing. To accomplish this the casing has threaded therein a plug 29 having a socket 30 in which is located a coil spring 31, a plug 32 being threaded in the socket and adapted to regulate the tension of the spring 31 when desired. Upon the upper terminal of the spring rests a disk 33 which engages the lower end of the stem 34, the upper end of which is secured to or rests against the bottom of the valve 14.

A stem 35 is carried by the plug 36 threaded in the dome 13, the lower end of said stem resting upon the weight 21. The plug 36 has contained in its socket 37, a coil spring 38,

the tension of which being regulated in the same manner as the springs 31 of the preferred form of the invention. It will thus be seen that the valve 14 will be resiliently balanced should it be desired to do so.

Having thus described the invention, I claim:

1. A valve of the class described comprising a casing, a guide sleeve carried by the casing, a valve seat in the casing, a hollow valve slidable in the sleeve, said valve having upper and lower ducts in its wall communicating with the interior thereof, a cap carried by the casing and providing a chamber, the upper ducts serving to discharge moisture from the chamber into the valve while the lower duct discharges the moisture therefrom into the casing.
2. A valve of the class described comprising a casing having a sleeve, a valve seat alined with the sleeve, a valve slidable in the sleeve, a cone confining the upper end of the valve when unseated, a cap engaged with the casing and having an annular groove therein, said cone having grooves therein communicating with the groove of the cap, and vents in the cap leading to atmosphere and the grooves of the cone.
3. A device of the class described comprising a casing having a sleeve and valve seat

alined with said sleeve, a valve slidable in the sleeve, a weight upon the valve, a flexible packing sheet mounted upon the valve and confined by the weight, a cone confining the weight when the valve is unseated, a cap, 35 said cap confining the cone and maintaining the sheet and cone fixed upon the casing.

4. A valve comprising a casing, a sleeve carried by the casing, a seat in the casing, said seat having an annular groove therein, 40 the bottom of the casing having an upstanding flange, a strainer engaged in the seat and having a ring adapted to engage said groove when the lower end of the strainer engages the flange, and a valve slidable in the sleeve 45 for cooperation with the seat.

5. A valve of the class described comprising a casing, said casing having a sleeve, a rim carried by the sleeve, a valve seat in the casing, a flexible packing sheet engaged with 50 the upper surface of the rim, a cone engaged with the packing sheet, a cap engaged with the rim and serving to hold the marginal portions of the packing sheet and cone engaged with the rim and a weight engaged 55 upon the packing sheet and confined by the cone.

In testimony whereof I affix my signature.

SCOTT V. SMITH.
